CLAIM

The ornamental design for a wall hanging, substantially as shown and described.

DESCRIPTION

FIG. 1 is a front elevational view of a wall hanging showing my new design;

FIG. 2 is a right side elevational view thereof; and

FIG. 3 is a left side elevational view thereof.

The back is plain and unornamented.

For clarity and ease of illustration, the side elevational views depict only the pouches on the nearest edge.
